[57] CLAIM

The ornamental design for a construction block face, as
shown and described.

DESCRIPTION

FIG. 1 is a perspective view of the construction block face
of this invention, the portions of the block being shown in
broken lines are for illustrative purposes only and form no
part of the claimed design;

FIG. 2 is a front elevation view of the block face of this
invention;

FIG. 3 is a side elevation of this invention;

FIG. 4 is a side elevation from the opposite of this invention;

FIG. 5 is a top plan view of this invention;

FIG. 6 is a bottom plan view of this invention; and,

FIG. 7 is a rear elevation view of the block face of this
invention.
